UNITED STATES PATENT OFFICE.

EDWARD L. SNADER, OF NEW YORK, N. Y.

THEATRICAL SCENIC ARCH.

SPECIFICATION forming part of Letters Patent No. 716,490, dated December 23, 1902.

Application filed October 15, 1902. Serial No. 127,348. (No model.)

To all whom it may concern:

Be it known that I, EDWARD L. SNADER, a citizen of the United States, residing at the city of New York, in the county and State of

5 New York, have invented a new and useful Improvement in Theatrical Scenic Arches for Producing Scenic Effects in Theatrical Performances, of which the following is a specification.

10 My invention relates to improvements in theatrical scenery and mechanical dramatic effects; and the object of my improvement is to provide a scenic arch which can be readily set up and which upon a given cue in the 15 progress of a theatrical performance will collapse and fall into pieces upon the stage, thus producing the dramatic effect of a disaster brought about by the sudden falling of an arch of masonry. I attain this object by the 20 mechanism illustrated in the accompanying drawing, which shows the arch A as it exists when set up ready for use on the stage, resting on the piers E E. The arch is composed, in the usual manner of a building-arch, of 25 wedge-shaped arch-stones a^2 a , a a^2 , resting unfastened (except by the cord hereinafter mentioned) one against another. It must, however, be so formed as to be in a high degree unstable by reason of the outthrust. 30 The arch-stones are made of wood, papier-mâché or other light material shaped and painted to represent masonry.

B is a cord passing freely around the arch and binding it securely together, the ends of 35 the cord being fastened at some convenient point d. It is necessary that the cord should pass over the extrados or upper surface of the arch, pressing every arch-stone under or through the end stones a^2 a^2 and through a 40 ring or channel D in the keystone at the crown of the arch, except that instead of passing under or through both of the end stones and being fastened at d the cord may, if desired, have its ends fastened upon opposite 45 sides of one only of the end stones, as at c and d. The cord should be of small size and so colored as not to be apparent to the audience.

The arch may be greatly varied in size and

shape and may be used to represent in part 50 a house, church, temple, bridge, or other structure, and several arches may be used at the same time.

When the cord is untied or severed at d or any convenient point, the arch, by reason of 55 its outthrust, will instantly collapse and fall into pieces. This loosening of the cord may be accomplished upon a cue by a stage-hand who is located in the wings of the theater or elsewhere out of sight of the audience.

60 The arch is best put together for use lying flat on its side on the stage. The cord is then bound around it in the manner already described. For convenience of application and to prevent accidental shifting it is well to 65 pass the cord through grooves or channels in the end stones, as b and b', and also through a ring or groove in the keystone at C. When thus bound together, the arch may be lifted into its final position upon the piers E E in any 70 convenient manner, preferably in the way that is usual in theaters—that is, by a rope let down from the flies and attached to a ring-bolt in the keystone at C.

75 The utility and originality of my invention consist in the manner of binding the arch-stones together, which, I believe, is the only way of securing these three advantages: First, the arch may be easily and quickly put together for use; second, it is secure against 80 accidental displacement while being lifted into position and afterward; third, it can be made to collapse upon a cue easily, quickly, and certainly.

85 What I claim as my invention, and desire to secure by Letters Patent, is—

The combination, in theatrical scenery, of an unstable arch of wood or other light material, with a cord binding the arch together, all substantially as set forth.

90 In testimony whereof I have signed my name to this specification in the presence of two subscribing witnesses.

EDWARD L. SNADER.
